UNITED STATES PATENT OFFICE.

GRAF GEORG VON ARCO, OF BERLIN, GERMANY, ASSIGNOR TO GESELLSCHAFT FÜR DRAHTLOSE TELEGRAPHIE M. B. H. HALLESCHES UFER 12/13, BERLIN, GERMANY, A CORPORATION OF GERMANY.

RECEIVING ARRANGEMENT FOR WIRELESS TELEGRAPHY.

Application filed April 30, 1923, Serial No. 635,409, and in Germany May 9, 1922.

Receiving arrangements for wireless communication are known which consist of single antenna located for apart and acting upon a common receiver which is usually arranged midway of the antennæ. On account of the distance between the antennæ, they are excited by the incoming wave in different current phases. The antennæ are then coupled to the common receiver in such a way that the different current phases are added together. The regulation of these arrangements to obtain the right current phase generally produces a coupling reaction and simultaneously a detuning.

The object of the invention relates to the provision of a one-way coupling such that a deleterious reaction is practically impossible. This offers the further advantage that the receiving apparatus is not supplied by the antennæ separately, but the antennæ are brought into a cascade arrangement, so that one of the antennæ receives the total energy, and the receiver is connected to such antenna only.

According to the invention, several antennæ of any kind, but preferably directive antennæ, for example, frame or loop antennæ, are used. Every frame or loop connected in the usual way to a vertical component may also have a one-sided cardioid field curve.

The single figure of the drawing represents an arrangement according to the invention. Only those parts are illustrated which are necessary for the description of the invention. Therefore, the anode and heating batteries required for the amplifiers are omitted.

1, 2 and 3 are frame antennæ which are arranged in the direction of the arrow, that is, in the direction of the incoming electric waves. 4 and 5 are radio frequency amplifiers, and 6 is an audion valve. 7, 8 and 9 are tuned intermediate loop circuits and 10 a telephone. The energy is transferred from the frame 1 to the frame 2 by the radio frequency amplifier tube 4, and the intermediate circuit 7. By using the tube 4 as a radio frequency amplifier, a one-sided coupling in the sense of the wave train is given. The phase of the energy which is supplied to the frame 2 from the frame 1 and to the frame 3 from the frame 2 is regulated in such a way that the phase-angle is identical

with that which is produced by the direct action of the wave on the frame antennæ 2 and 3. The frames 1, 2, and 3 are connected by the anode and cathode wires of the valves, and as these connections contain the very high ohmic resistance of the valve itself, copper connecting lead wires of very small sectional area may be used. The wires may even be shunted by resistances 11, 12 at one or more places in order to prevent atmospheric or other local disturbances.

At the end of the anode-cathode circuit of the tube 4, the closed oscillatory circuit 7 is attached, by the adjustment and coupling of which the current is transferred to the antenna 2 in the right phase, and from there the energy is supplied by the radio frequency amplifier 5 over the intermediate circuit 8 to the frame antenna 3. The total receiving energy is then withdrawn from the last antenna 3 and conducted over the intermediate circuit 9 and the amplifying arrangement including the audion tube 6 to the telephone 10.

The whole arrangement constitutes a receiving system which in the main is of the one-sided or cardioid type.

As the energy is only added together for the special phase displacement, this arrangement is little influenced by a shock excitation such as is caused by an atmospheric disturbance.

Having described my invention, what I claim is:

1. A circuit arrangement comprising a plurality of directive antennæ spaced from each other in the direction of propagation of the wave which it is desired to receive and amplifiers for supplying energy from one to another of the antennæ in cascade arrangement.

2. A radio receiving apparatus comprising a plurality of directive antennæ spaced from each other, and vacuum tube amplifiers for coupling the antennæ together so as to supply energy from preceding to succeeding antennæ in cascade arrangement.

3. A radio receiving apparatus comprising a plurality of loop antennæ spaced from each other in the general direction of propagation of the wave which it is desired to receive and by a distance suited to the length of the wave, and means for transmitting energy from one of the antennæ to another at

- the same phase-angle as the wave energy received in the second antenna from space.
4. A radio receiving apparatus comprising a plurality of loop antennæ spaced from each other in substantial alignment in the planes of the antennæ, and means for transmitting energy received in one of the antennæ to another of the antennæ, said means comprising a vacuum tube amplifier having a loop circuit coupled to the second antenna and constructed to enable the amplified energy from the first antenna to be supplied to the second antenna at the same phase as the energy received in the second antenna from space.
5. A radio receiving apparatus comprising a number of loop antennæ greater than two spaced from each other in substantial alignment in the planes of the antennæ and provided with condensers and means for supplying energy in cascade relation from preceding to succeeding antennæ, said means comprising vacuum tube amplifiers having tuned circuits coupled to the succeeding antennæ and arranged in the output circuits of the amplifiers, and said amplifiers having their input circuits connected to the preceding antennæ at opposite sides of said condensers.
6. In combination, a source of radiant energy, a plurality of receiving antennæ spaced from each other and substantially in line with said source, each antenna being capable of receiving energy from said source, and land conductor and amplifying means associated therewith for transferring received energy from one antenna to a second antenna, and signal responsive means associated with said second antenna.
7. In combination, a source of radiant energy, a plurality of receiving directive antennæ spaced from each other and substantially in line with said source, each antenna being capable of receiving energy from said source, and land conductor and amplifying means associated therewith for transferring received energy from one antenna to a second antenna, and signal responsive means associated with said second antenna.
8. A circuit arrangement comprising a plurality of antennæ spaced from each other in the direction of propagation of the wave which it is desired to receive, means for connecting said antennæ in cascade, and means intermediate the antennæ for amplifying the energy delivered by one antenna to the next antenna of the cascade.
9. A circuit arrangement comprising a plurality of antennæ spaced from each other and connected in cascade, and means for amplifying the energy from one to another of the antennæ of the cascade.
10. A circuit arrangement comprising a plurality of antennæ connected in cascade, and means for amplifying the energy from one to another of the antennæ of the cascade.
11. A circuit arrangement comprising more than two antennæ spaced from each other in the direction of propagation of the wave which it is desired to receive, means for connecting said antennæ in cascade, and one-way coupling means for supplying energy from one to another of the antennæ of the cascade.
12. A circuit arrangement comprising more than two antennæ spaced from each other and connected in cascade, and one-way coupling means for supplying energy from one to another of the antennæ of the cascade.
13. A circuit arrangement comprising more than two antennæ connected in cascade, and one-way coupling means for supplying energy from one to another of the antennæ of the cascade.
14. In combination, more than two receiving loop antennæ spaced apart and located substantially in the same plane, means for transferring energy from one antenna to a second antenna in cascade arrangement thereto, and signal responsive means associated with said second antenna.
15. A radio receiving apparatus comprising a plurality of antennæ spaced from each other in substantial alignment in the planes of the antennæ, and means for transmitting energy received in one of the antennæ to another of the antennæ, said means comprising a vacuum tube amplifier having a loop circuit coupled to the second antenna and constructed to enable the amplified energy from the first antenna to be supplied to the second antenna at the same phase as the energy received in the second antenna from space.
16. A circuit arrangement comprising a plurality of antennæ spaced from each other, and land conductor and amplifying means associated with said antennæ, said means being adapted to impress on the second antenna from the first antenna an amplified signal in phase with the signal picked up by the said second antenna.
